TONNAGE CALCULATOR

Robert J. Dresher, Dayton, Ohio

Application December 14, 1949, Serial No. 132,850

4 Claims. (Cl. 235—88)

1

This invention relates to improvements in tonnage calculators and particularly to a means for quickly calculating the force required to punch a blank from sheet metal, for calculating the force required for stripping the punched blank from the die, and for determining the size of the die required to withstand the pressure.

In designing punch and die sets, the forces for punching and stripping blanks in a punch and die set require time-consuming calculations, because the forces required are dependent on the size of the blank to be punched, its thickness, and the kind of material used.

Another problem is to determine whether or not a given punch press has sufficient power to punch out the parts, so that it can be predetermined which punch press can be used and the die set designed for mounting on the selected punch press.

The principal object of the invention is to provide a calculator for determining all factors required for designing a punch and die set for a given blank to be punched.

It is a specific object of the invention to provide a simple calculator for determining the tonnage required for punching out a blank and for stripping the blank from the punch of a punch and die set, and the area required for the base of a punch of the punch and die set to support the load placed thereon during a punching operation.

Another specific object of the invention is to provide a calculator having certain factors embodied therein, which factors can be determined by setting a movable element relatively to a common scale.

With these and incidental objects in view, the invention includes certain novel features of construction and combinations of parts, a preferred form of which is hereinafter described with reference to the drawings which accompany and form a part of this specification.

Of said drawings:

Fig. 1 is an elevational view showing one face of the calculator.

Fig. 2 is a cross-sectional view taken on line 2—2 and looking in the direction of the arrows.

Fig. 3 is a detail view of one element of the calculator containing certain factors.

Fig. 4 is a detail view of the opposite side of the element shown in Fig. 3 and shows additional factors thereon.

General description

Before a punch and die set can be properly designed to fit a selected punch press, the tonnage required to punch out a blank from a given material must be determined, so that the punch and die set can be designed to fit the punch

press, or vice versa, so that it can be determined if a given punch press has sufficient tonnage capacity to do the work required.

It is also necessary to determine the pounds pressure required to strip the blank from the punch, so that springs of the proper strength usually employed for this purpose can be supplied.

Another factor to be determined is the minimum square area required for the base of the punch, so that the punch can withstand the load placed thereon when the punching operation is performed.

The above factors are governed by the length of the cutting edges of the part to be blanked, and the kind and thickness of the material.

The first step in the calculations is to measure the total length of the cutting edges of the part to be blanked. If the part is a solid piece, containing no openings or holes, the length of the perimeter is first measured. If openings are to be simultaneously punched in the piece, the perimeter of the opening or openings is measured and the total thereof calculated. The present scale has these lengths calibrated in inches and graduated on the outer edge of the calculator dial. A disk having windows therein, to expose factors corresponding to various materials, is rotated on the calculator disk until a pointer thereon coincides with the total length calculated. The factor in tons necessary to punch the blank is then read from the selected window. Thus the first factor is obtained.

To obtain the pounds pressure necessary to strip the blank from the punch, the above-mentioned pointer coincides with the said scale on the calculator dial, and this time the scale represents tons instead of inches. After the said pointer has been set into the second position relatively to the scale, the pounds pressure required is read from the scale marked "stripping scale" on Fig. 1 of the drawings. It may be noted at this point that the "stripping scale" shown herein is calibrated to 5% of the tonnage required for punching, as this has been found satisfactory for small parts.

The next factor—that is, the area required to safely support the punch—is read from a scale marked "area scale" on the drawings. This factor is read through a window in the rotatable disk while the pointer thereon is in the tonnage selecting position.

Detailed description

The calculator includes a dial 10, having factors suitably located on each side thereof, as shown in Figs. 3 and 4, each side being calibrated for materials of different thicknesses. A disk 11, having a series of windows 12, 13, 14, 15, and 16, is mounted on an arbor 17, on which the dial 10

and the disk 11, together with a second disk 20, can be rotated. The dial 10 and the disks 11 and 20 are positioned on the arbor 17, where a head 18 of the latter and a washer 19 staked to the arbor maintain the calculator in assembled position. The arbor 17 is of a size to permit easy rotation of the parts thereon.

The window 12 is located in the disk 11 in a position wherein sections of the scales 21, 22, and 23 can be exposed to view upon rotation of the dial 10. Similarly, sections of scales 24, 25, and 26 can be exposed to view through window 13; sections of scales 27, 28, and 29 can be exposed through window 14; sections of scales 30, 31, and 32 can be exposed through window 15; and sections of scales 33, 34, and 35 can be exposed through window 16. Sections of a scale 36 can be exposed through a window 37, and sections of a scale 38 can be exposed through a notch or window 39 on the perimeter of the disk 11. Also, lying outside the perimeter of the disk 11, is a scale 40, which is always exposed to view in its entirety. The scale 40 serves a dual purpose, explained later.

The scales 21 to 35 inclusive are calibrated to indicate the tons pressure required for materials of various thickness and condition. For example, scale 21 is calibrated to indicate tonnage factors for soft material, .062 inch thick; the scale 22 is calibrated to indicate tonnage factors for $\frac{1}{4}$ – $\frac{1}{2}$ hard material, .062 inch thick. The legends on Fig. 1 indicate the calibration for the various materials for each of the scales shown in Fig. 4. The scales shown in Fig. 3 are calibrated to indicate the tonnage factor for materials .020, .030, .040, .050, and .060 inch thick and for three degrees of hardness, like that shown in Fig. 4. The disk 20 covers the various scales and is provided with windows similar to those shown in Fig. 1 to selectively expose sections of these scales.

Operation

For the purpose of describing the operation of the invention, the finding of the various factors required for a part having a perimeter of 37 inches and made of soft material .062 inch thick will be used.

The first step is to set a pointer 45 (Fig. 1) on the disk 11 opposite the graduation indicating 37 on the scale 40. After this is done, a reading is taken from the scale 21 by observing the graduation at the right-hand edge of window 12. This setting will indicate 30, which factor is calibrated in tons, and therefore it is determined that it will take 30 tons to punch out the blank.

The second step is to set the pointer 45 to indicate 30 on the scale 40. The scale 40 is used first to indicate "inches," and for the second step the scale 40 is used to indicate "tons." After the pointer 45 has been set to indicate 30 tons on the scale 40, the "pounds" pressure required to strip the blank from the punch is indicated by a pointer 46, which points to the factor "3,000 pounds" on the scale 38.

The third required factor is the necessary area of the base of the punch which is required to withstand the pressure applied during the punching operation. This factor is read through the window 37 (Fig. 1) when the pointer 45 is set to "30" on scale 40, and is indicated by the pointer 47, which in the example assumed points to 10, which is the area in square inches required when based on 3 tons per square inch, the rate found adequate.

While the form of the invention shown and

described herein is admirably adapted to fulfill the objects primarily stated, it is to be understood that it is not intended to confine the invention to the one form or embodiment disclosed herein, for it is susceptible of embodiment in various other forms.

What is claimed is:

1. In a device of the class described, the combination of a base member having a plurality of tonnage scales thereon; a second member mounted on and movable relatively to the base member, said second member having a plurality of windows therein, each window overlying a different one of said tonnage scales; another scale on the base member and located adjacent the perimeter thereof, said another scale indicative of the size of a blank to be punched and being correlated with the plurality of tonnage scales; a pointer on the second member and located adjacent the another scale to guide the setting of the second member into a position in relation to the another scale, said pointer also correlated with the windows in said second member to expose sections of the plurality of scales to view, the windows representing materials of different thickness and degrees of hardness, the plurality of scales being so proportioned and angularly related with the windows as to jointly indicate the tonnage required to punch out a part of given size and character, said pointer on the second member also angularly related to the said another scale so as to indicate the said tonnage requirement; a second pointer on the second member; and a scale on the base member angularly related with the second pointer to indicate the stripping pressure in pounds required to strip the punched part from the punch when the first pointer is set to indicate tonnage on the said another scale.
2. In a device of the class described, the combination of a base member having a plurality of tonnage scales thereon; a second member mounted on and movable relatively to the base member, said second member having a plurality of windows therein, each window overlying a different one of said tonnage scales; another scale on the base member and located adjacent the perimeter thereof, said another scale indicative of the size of a blank to be punched and being correlated with the plurality of tonnage scales; a pointer on the second member and located adjacent the another scale to guide the setting of the second member into a position in relation to the another scale, said pointer also correlated with the windows in said second member to expose sections of the plurality of scales to view, the windows representing materials of different thickness and degrees of hardness, the plurality of scales being so proportioned and angularly related with the windows as to jointly indicate the tonnage required to punch out a part of given size and character, said pointer on the second member also angularly related to the said another scale, so as to indicate the said tonnage requirement; a second pointer on the second member; a scale on the base member angularly related with the second pointer to indicate the stripping pressure in pounds required to strip the punched part from the punch when the first pointer is set to indicate tonnage on the said second scale; an area scale on the base member; and a window in the second member correlated with the first pointer and the area scale to indicate the base area required for a punch capable of withstanding the tonnage indicated by the said first pointer.

3. In a device of the class described, the combination of a base member having a plurality of tonnage scales thereon; a second member mounted on and movable relatively to the base member, said second member having a plurality of windows therein, each window overlying a plurality of said tonnage scales, which are correlated to indicate tonnage requirements for a specific thickness of material to be punched; another scale on the base member and located on the perimeter thereof, said another scale indicative of the length of the cutting edges of the punch for punching a blank and being correlated with the plurality of tonnage scales; a pointer on the second member located adjacent said another scale to guide the setting of the second member into a position in relation to the said another scale, said pointer also correlated with the said windows to expose sections of the plurality of scales to view to indicate the tonnage required to punch out a part of a given thickness and degree of hardness, said pointer on the second member also angularly related to said another scale so as to indicate the said tonnage requirement; a second pointer on the second member; and a scale on the base member angularly related with the second pointer to indicate the stripping pressure in pounds required to strip the punched part from the punch, when the first pointer is set to indicate tonnage on the said another scale.

4. In a device of the class described, the combination of a base consisting of a disk and having a plurality of tonnage scales arranged thereon in parallel circular form; a second disk rotatably mounted on the base at the center thereof, said second disk being smaller in diameter than the

first disk to expose an area of said first disk at the perimeter thereof, said second disk covering the area containing the said plurality of scales; a plurality of windows in said second disk, each window registering with one of said plurality of scales to expose sections of said plurality of scales to view; another scale in the said area exposed on the base at the perimeter thereof and calibrated for indicating measurement of length and of tonnage; an indicator on the smaller disk correlated with the tonnage scales so that when the indicator is set to indicate a length on the said another scale the tonnage required to punch a part of the selected dimension is indicated on the tonnage scales, and said pointer thereafter settable on the said another scale to indicate said tonnage; a scale on the base member located between the said another scale and the tonnage scales; and a second indicator correlated with the first indicator and the last-named scale to indicate pounds pressure required for stripping the blank from the punch.
